UNITED STATES PATENT OFFICE

ANDREW ROSENTHAL, OF NEW YORK, N. Y.

CAM FAUCET

Application filed June 23, 1928. Serial No. 289,008.

This invention relates to improvements in faucets for controlling the flow of fluids and liquids.

Objects

5 Among the principal objects which the present invention has in view are: to provide a novel cam means for operating the faucet; to simplify the construction and reduce the number of parts of the faucet; to improve and augment the efficiency of the construction; and to provide a faucet of pleasing and ornamental appearance as well as one which is reliable in service.

10 Other objects and advantages of the invention will appear as the description proceeds.

Drawings

20 Figure 1 is a sectional view partly in elevation of a faucet constructed in accordance with the present invention;

Figure 2 is a sectional view taken as on the line 2—2 of Figure 1;

25 Figure 3 is a transverse sectional view taken as on the line 3—3 of Figure 1; and

Figure 4 is a plan sectional view taken as on the line 4—4 of Figure 1.

Description

30 The preferred embodiment of the invention in detail comprises a body portion 10 provided with a bottom outlet 11, and a side inlet 12 having a screw-fitted connection with a nipple 13, which is adapted for adjustment 35 in service to the water line. The body portion 10 is hollow and contains a movable valve member 14 having a cushion element 15 attached to the end thereof as by a set screw 16. The cushion member co-operates with the 40 end of the nipple 13 and the valve member may be moved transversely in the body portion to control the flow of fluid through the nipple emitting from the outlet 11.

45 As best shown in Figures 1 and 4, the valve member 14 is partially telescoped in a hollow plug 17 which has a screw-threaded connection in the body portion opposite the inlet 12.

A coil spring 18 is positioned within the hollow plug and serves to bias the valve member 50 to its closed position in which the cushion

15 abuts the end of the nipple 13 and prevents the flow of liquid. The plug is provided with a slot 19 in which rides a projection 20 on the valve member, the slot and projection serving to guide the valve member for pure rectilinear movement back and forth in the body portion and prevent rotation of the valve member.

55 The means for imparting movement to the valve member and thus operating the faucet includes a stud or similar element 21 associated with the valve member and projecting upwardly into operating relation with a cam 22, as shown in Figure 2, which cam when rotated engages the stud and thus causes movement of the valve member for opening or closing the faucet. The cam 22 rests upon the seat 23 formed on the interior of the body portion of the faucet and a nut 24 is screw-threaded in the body portion above the cam 60 and serves to maintain the cam in proper disposition on the seat in service. The cam has an operating stem 25 which projects vertically through the nut and is provided at its upper end with an operating handle 26. The 65 cam may also be provided with a stud 27 which serves as a stop to allow only a limited rotation of the cam.

70 In the operation of the faucet, when in closed position, the movable valve member 80 14 is urged to its extreme right position as seen in Figure 1 by the spring 18 and prevents the flow of any liquid through the faucet. When it is desired to operate the faucet, the handle 26 is turned and the cam 22 acts on 85 the stud 21 to move the valve and open the faucet to allow flow of liquid through the outlet 11, the movement occurring against the action of the spring 18 which is compressed. When the handle is turned again so that the 90 cam releases the stud 21 the spring urges the valve member back to its closed position and checks the further flow through the faucet.

95 It will be understood that the variations and modifications in the specific construction described may be resorted to in the practise of the invention, and I therefore desire to be limited only by the state of the prior art and the scope of the appended claims.

I claim:

1. A faucet comprising a hollow body having fluid inlet and outlet passages and a passage for the valve operating mechanism, a valve member slidably mounted in said body, a stud carried by said valve member, said last mentioned passage being formed with an internal annular bearing seat, a cam rotatably mounted on said seat and having cooperative engagement with said stud, and an operating handle connected with said cam for operating the same.
2. A faucet comprising a hollow body having fluid inlet and outlet passages and a passage for the valve operating mechanism, a valve member slidably mounted in said body, means for preventing rotation of said valve member, a stud carried by said valve member, said last mentioned passage being formed with an internal annular bearing seat, a cam rotatably mounted on said seat and having cooperative engagement with said stud, and an operating handle connected with said cam for operating the same.
3. A faucet comprising a hollow body having fluid inlet and outlet passages and a passage for the valve operating mechanism, a valve member slidably mounted in said body, means for preventing rotation of said valve member, resilient means for normally forcing said valve member to closed position, a stud carried by said valve member, said last mentioned passage being formed with an internal annular bearing seat, a cam rotatably mounted on said seat and having cooperative engagement with said stud, and an operating handle connected with said cam for operating the same.
4. A faucet comprising a hollow body having fluid inlet and outlet passages and a passage for the valve operating mechanism, a valve member slidably mounted in said body, means for preventing rotation of said valve member, said last mentioned passage being formed with an internal annular bearing seat, a cam rotatably mounted on said seat and having cooperative engagement with said stud, means carried by said cam for limiting its rotation, and an operating handle connected with said cam for operating the same.

50 ANDREW ROSENTHAL.
